T. H. THOMAS ET AL

FLUID PRESSURE BRAKE

Filed Oct. 24, 1927

UNITED STATES PATENT OFFICE.

THOMAS H. THOMAS, OF EDGEWOOD, AND CLAUDE A. NELSON, OF WILMERDING, PENNSYLVANIA, ASSIGNORS TO THE WESTINGHOUSE AIR BRAKE COMPANY, OF WILMERDING, PENNSYLVANIA, A CORPORATION OF PENNSYLVANIA.

FLUID-PRESSURE BRAKE.

Application filed October 24, 1927. Serial No. 223,204.

This invention relates to automatic train control apparatus and in particular to the type having automatic means for effecting a split or two stage reduction in brake pipe pressure.

In applying the brakes on a train, the usual practice of an engineman is to first effect a light application of the brakes and then after the elapse of a time interval sufficient to gently gather the slack in a train, a second and heavier application of the brakes is made in order to apply the desired stopping force to the cars in the train.

The principal object of our invention is to provide an improved automatic split or two stage reduction apparatus having means whereby a time interval will elapse between the start of the first reduction and the start of the second reduction.

In the accompanying drawing, the single figure is a diagrammatic view of a fluid pressure automatic train control apparatus embodying our invention.

As shown in the drawing, the train control apparatus may comprise an automatic brake valve device 1, a magnet valve device 2, two feed valve devices 3 and 4, and a split or two stage reduction valve device.

The automatic brake valve device is of the usual type employed with automatic train control apparatus and comprises a casing having a chamber 5 containing a rotary valve 6 adapted to be operated by a handle 7 and also having the usual equalizing piston mechanism, which comprises an equalizing piston 8 forming, at one side, a chamber 9 and forming at the opposite side a chamber 10 connected to the usual brake pipe 11 through passage 12, said equalizing piston being adapted to operate a brake pipe discharge valve 67. Associated with the brake valve device is a brake pipe cut-off valve mechanism, which comprises a cut-off valve 13 contained in a chamber 14 and adapted in one position to seal on a seat ring 15. Said cut-off valve is connected to a piston 16 contained in a chamber 17 and is adapted to be operated by said piston. A spring 18

contained in the piston chamber 17 opposes downward movement of the piston 16.

Preferably associated with the brake valve device is a brake application valve portion, which comprises an application piston 19 contained in a chamber 20 and a slide valve 21 contained in a chamber 22 and adapted to be operated by said piston. Outward movement of the application piston 19 is opposed by the pressure of a spring 23 contained in the chamber 20.

The magnet valve device 2 comprises a magnet adapted to operate a valve 24 contained in a chamber 25, said valve being opposed in seating by the pressure of a spring 28. When the magnet is deenergized, as in territory governed by unfavorable track conditions, the spring 28 unseats the valve 24, so as to connect the application piston chamber 20 to the atmosphere by way of passage and pipe 26 and the atmospheric exhaust passage 27. Upon energization of the magnet, as in territory where the track conditions are favorable, the valve 24 is seated so as to cut off communication between the application piston chamber and the atmosphere.

The split or two stage reduction valve device comprises a repeater valve portion 29, a hold back valve portion 30, an equalizing valve portion 31 and a maintaining valve portion 32.

The repeater valve portion 29 comprises a piston 33 contained in a chamber 34 and a slide valve 35 contained in a chamber 36 and adapted to be operated by said piston, which piston is opposed in outward movement by the pressure of a spring 37 contained in the piston chamber 34.

The hold back valve portion 30 comprises a piston 38 contained in a chamber 39 and a slide valve 40 contained in a chamber 41 and adapted to be operated by said piston, which piston is opposed in outward movement by the pressure of a spring 42 contained in the piston chamber 39.

The equalizing valve portion 31 comprises a diaphragm 43 open at one side to a cham-

ber 44 and having at the opposite side a valve chamber 45. Secured to said diaphragm is an upwardly extending stem 46, having two flanges adapted to engage and operate a slide valve 47.

The maintaining valve portion 32 comprises a diaphragm 48 open at one side to the diaphragm chamber 44 and having at the opposite side a chamber 49. A maintaining valve 50 is contained in a chamber 51 and has a fluted stem extending through a wall of the casing and into the diaphragm chamber 49, wherein said stem engages the depending stem of a follower 52, which follower is held in engagement with the diaphragm 48 by the pressure of a spring 53 on the valve 50.

In operation, fluid under pressure from a main reservoir 54 is supplied through pipes 20 and passages 55 to the rotary valve chamber 5 of the automatic brake valve device, the application valve chamber 22, the repeater valve chamber 36 and to the two feed valve devices 3 and 4. Fluid under pressure from the application valve chamber 22 then flows through a port 56 in the application piston 19 to the application piston chamber 20, and from thence through passage and pipe 26 to the magnet valve device 2. If the track conditions are favorable, the magnet of the magnet valve device 2 is energized and the magnet valve 24 seated. The fluid pressure thus equalizes on the opposite sides of the application piston 19, so that the pressure of spring 23 is permitted to shift the application piston 19 and slide valve 21 to the release position, as shown in the drawing.

In the release position of the application slide valve, fluid at main reservoir pressure flows from the application valve chamber 22 to the repeater valve piston chamber 34 by way of port 57 in the application slide valve 21 and passage and pipe 58. The fluid pressure thus becomes substantially equal on the opposite sides of the repeater piston 33, so that the pressure of spring 37 is permitted to shift the repeater piston 33 and slide valve 35 to the release position, as shown in the drawing.

Fluid at the usual reduced pressure employed in the brake pipe is supplied by the feed valve device 3 to the seat of the brake valve rotary valve 5 through pipe and passage 94, and with the brake valve in running position, fluid at the reduced pressure flows from passage 94 through cavity 59 in the rotary valve 5 and passage 60 to the cut-off valve chamber 14, and also from passage 60 through cavity 61 in the application slide valve 21, and passage 62 to the cut-off valve piston chamber 17. The opposing fluid pressures on the cut-off valve piston 16 thus being equal, the pressure of spring 18 holds the cut-off valve 13 in its open position, as

shown in the drawing, in which position fluid at the reduced feed valve pressure flows from the valve chamber 14, through a chamber 63 formed intermediate the seat ring 15 and piston 16, and through passage 12 to the equalizing piston chamber 10 and to the brake pipe 11, thereby charging said chamber and brake pipe.

Fluid at the reduced pressure supplied by the feed valve device 3 also flows through cavity 59 in the brake valve rotary valve 5 to the equalizing piston chamber 9 by way of passage 64, cavity 65 in the application slide valve 21 and passage 66. The fluid pressures thus become equal on the opposite sides of the equalizing piston 8, so that said piston operates to hold the brake pipe discharge valve 67 seated. Fluid under pressure from passage 66 also flows through a choked passage 68 and passage and pipe 69 to a No. 1 equalizing reservoir 70 and to the diaphragm chamber 44 of the split reduction device, thereby charging said reservoir and chamber to substantially the same pressure as in the brake pipe.

The No. 1 equalizing reservoir pressure acting in diaphragm chamber 44 deflects the equalizing diaphragm 43 upwardly, which causes the slide valve 47 to be shifted, so as to uncover the passage 71. Fluid at main reservoir pressure from the repeater valve chamber 36 then flows through said passage 71 to the equalizing valve chamber 45 and from thence to a No. 2 equalizing reservoir 72 through passage and pipe 73. When the fluid pressure in the equalizing valve chamber 45 and the No. 2 equalizing reservoir becomes substantially equal to the pressure in diaphragm chamber 44, the balanced fluid pressures acting on the equalizing diaphragm 43, causes the equalizing slide valve 47 to be shifted downwardly again and the lap the passage 71.

Fluid under pressure from the brake pipe 11 is supplied to the maintaining diaphragm chamber 49 through passage 11, and since when the brake system is charged, the brake pipe pressure is substantially equal to the pressure of the fluid in the No. 1 equalizing reservoir 70 and the diaphragm chamber 44, the diaphragm 48 is in a balanced condition, so that the pressure of spring 53 is permitted to hold the maintaining valve 50 seated.

Fluid at the reduced pressure employed in the operation of the split reduction device is supplied by the feed valve device 4 to a timing reservoir 74, and to the hold back piston chamber 39 by way of pipe and passage 75, cavity 76 in the repeater slide valve 35 and passage and pipe 77. Fluid from the feed valve device 4 is also supplied to the hold back valve chamber through pipe and passage 75. The fluid pressures thus being equal on the opposite sides of the hold back piston, the pressure of spring 42 normally

holds the hold back piston and slide valve in the position, as shown in the drawing.

With the application valve portion in the release position, a first reduction reservoir 78 is vented to the atmosphere through pipe and passage 79, cavity 80 in the application slide valve 21 and through the exhaust passage 81, while a second reduction reservoir 82 is vented to the atmosphere through a pipe and passage 83, cavity 84 in the brake valve rotary valve 6 and the exhaust passage 85.

If a train enters territory governed by unfavorable track conditions, the magnet of the magnet valve device is deenergized and the spring 28 then unseats the magnet valve 24, which permits the fluid pressure to be vented from the application piston chamber 20 to the atmosphere through passage and pipe 26 and the atmospheric exhaust passage 27. The fluid at main reservoir pressure in the application valve chamber 21 then shifts the application piston 19 and slide valve 21 outwardly to application position, in which position the cut-off valve piston chamber 17 is vented to the atmosphere through passage 62, cavity 61 in the application slide valve 21 and the atmospheric passage 86. The opposing pressure of the brake pipe fluid on the cut-off valve piston 16, then shifts said piston downwardly against the pressure of spring 18 and thereby causes the cut-off valve to seal on the seat ring 15 and prevent further flow of fluid under pressure to the brake pipe.

In application position of the application slide valve, the repeater piston chamber 34 is vented to the atmosphere through passage and pipe 58, cavity 80 in the application slide valve and the exhaust passage 81, so that the pressure of the main reservoir fluid in the repeater valve chamber 36 is permitted to shift the repeater piston 33 and slide valve 35 outwardly to the application position, in which position the passage 71 leading to the seat of the equalizing slide valve 47 is lapped and the No. 1 equalizing reservoir 70 is connected to the No. 2 equalizing reservoir 72 through pipe and passage 69, cavity 87 in the repeater slide valve 35, passage 88, cavity 89 in the hold back slide valve and passage 73, thereby providing an enlarged volume of equalizing reservoir, for reasons to be hereinafter explained.

In application position of the application slide valve 21 the supply of fluid pressure from the brake valve device 3 to the No. 1 equalizing reservoir 70 and to the equalizing piston chamber 9 is cut off and said reservoir and chamber are connected to the first reduction reservoir 78 through passage 69, past a ball check valve 90 and at the same time through the choked passage 68, through the passage 66, cavity 65 in the application slide valve 21 and choked passage and pipe 79. Fluid pressure from both the No. 1 and

No. 2 equalizing reservoirs then equalizes into the first reduction reservoir and thereby causes a predetermined reduction in pressure in the equalizing reservoirs No. 1 and No. 2 and in the pressure acting in chamber 9 upon the equalizing piston 8, which piston then operates the brake pipe discharge valve 67 to cause a corresponding reduction in brake pipe pressure, in the well known manner.

In application position of the repeater slide valve 35, the hold back piston chamber 39 and the timing reservoir 74 are connected to the atmosphere through passage and pipe 77, cavity 76 in the repeater slide valve 35 and through a choked atmospheric passage 91, and the pressure of the fluid in said chamber and reservoir thereby reduces at a predetermined rate. When said pressure is thus reduced a predetermined degree, the higher feed valve pressure acting in the hold back valve chamber 41 shifts the hold back piston 38 and slide valve 40 downwardly to the second reduction position, in which position the passages 88 and 73 leading to the No. 1 and No. 2 equalizing reservoirs, respectively, are disconnected from each other and the second reduction reservoir 82 is connected to the first reduction reservoir 78 through pipe and passage 83, cavity 89 in the hold back slide valve 40 and passage and pipe 79. The pressure of the fluid in the No. 1 equalizing reservoir 70, the equalizing piston chamber 9 and in the connected first reduction reservoir 78 is thus permitted to further reduce by flow to the second reduction reservoir 82 and thereby cause the equalizing mechanism to again operate and cause a corresponding second reduction in brake pipe pressure.

In order to limit the total degree of brake pipe reduction to that necessary to effect a full service application of the brakes, the brake valve handle is turned to lap position, in which position the passage 88 from the second reduction reservoir 82 is lapped, so that the second reduction in the pressure of the fluid in the No. 1 equalizing reservoir is thereby limited to the equalization into the two reduction reservoirs.

The rate of reduction in brake pipe pressure can not exceed the rate at which the pressure in the equalizing reservoir volume is reduced, since if leakage of fluid under pressure from the brake pipe to the atmosphere is so severe as to tend to cause the brake pipe pressure to decrease at a rate faster than the equalizing reservoir pressure reduces, the brake pipe pressure acting on the diaphragm 48 of the maintaining portion 32 permits the higher equalizing reservoir pressure in chamber 44 to deflect the diaphragm 48 downwardly and unseat the maintaining valve 50, which permits main reservoir fluid to flow from the repeater valve chamber 36 into the brake pipe by way of

passage 92 and past the unseated valve 50. When the brake pipe pressure has been increased a degree substantially equal to the No. 1 equalizing reservoir pressure acting in the diaphragm chamber 44, the pressure of spring 53 seats the maintaining valve 50 and thereby prevents further increase in the brake pipe pressure.

With a train operating in territory governed by favorable track conditions, the engineer may manually effect a brake application in the usual manner, since only the No. 1 equalizing reservoir 70 is connected to the brake valve device, which reservoir corresponds in volume to that employed in the usual locomotive brake equipment.

In manually making a brake application, the No. 1 equalizing reservoir pressure acting in diaphragm chamber 44 is reduced through the brake valve device in the usual manner and the higher pressure of the No. 2 equalizing reservoir fluid acting in the equalizing valve chamber 45, deflects the diaphragm 43 downwardly, which causes the slide valve 47 to be shifted so as to connect the No. 2 equalizing reservoir and the equalizing valve chamber 45 to the atmosphere through the exhaust passage 93, thereby permitting the No. 2 equalizing reservoir pressure to reduce at the same rate as the No. 1 equalizing reservoir pressure is reduced. This is desirable, for if an automatic brake application is initiated in the manner hereinbefore described, such automatic application may then continue the reduction in equalizing reservoir pressure from the point at which the manual application is stopped. If the No. 2 equalizing reservoir pressure is not reduced with the No. 1 equalizing reservoir pressure during a manual brake application, then if an automatic brake application should be started, the higher pressure in the No. 2 equalizing reservoir would have to be reduced before any further reduction in brake pipe pressure could be effected.

As hereinbefore described, the No. 1 and No. 2 equalizing reservoirs are connected together during the first reduction and the No. 2 equalizing reservoir is cut out or inoperative during the second reduction. Since the rate at which the pressure of the equalizing reservoir volume is reduced is controlled through the choked portion of passage 79 in the application portion, during both the first and second reductions, the rate at which the pressure in the connected equalizing reservoirs is reduced during the first reduction is slower than the rate at which the pressure in the single No. 1 equalizing reservoir is reduced during the second reduction. The slow rate of initial reduction is adapted to apply the train brakes at such a rate as to provide adequate time for gently gathering the slack between the cars in a train, and after such slack is

gathered then the faster rate of reduction which occurs during the second reduction is such as to cause a brake application of the desired force for effectively stopping the train.

While one illustrative embodiment of the invention has been described in detail, it is not our intention to limit its scope to that embodiment or otherwise than by the terms of the appended claims.

Having now described our invention, what we claim as new and desire to secure by Letters Patent, is:—

1. The combination with a brake pipe, of means for effecting a reduction in brake pipe pressure in two stages including two equalizing reservoirs, two reduction reservoirs, means for venting fluid from both equalizing reservoirs to one reduction reservoir to effect the first reduction in brake pipe pressure, a timing reservoir, and a valve device operated upon a predetermined reduction in pressure in said timing reservoir for connecting one reduction reservoir with the other.

2. The combination with a brake pipe, of means for effecting a reduction in brake pipe pressure in two stages including two equalizing reservoirs, two reduction reservoirs, means for venting fluid from both equalizing reservoirs to one reduction reservoir to effect the first reduction in brake pipe pressure, a timing reservoir, and a valve device operated upon a predetermined reduction in pressure in said timing reservoir for separating one equalizing reservoir from the other and for connecting the two reduction reservoirs.

3. The combination with a brake pipe, of means for effecting a reduction in brake pipe pressure in two stages including two equalizing reservoirs, two reduction reservoirs, means for venting fluid from both equalizing reservoirs to one of the reduction reservoirs to effect the first stage of reduction in brake pipe pressure and for venting fluid from only one of said equalizing reservoirs to both reduction reservoirs to effect the second stage of reduction in brake pipe pressure, a timing reservoir, and a valve device included in said last mentioned means and operated upon a predetermined reduction in pressure in the timing reservoirs for connecting one reduction reservoir with the other.

4. The combination with a brake pipe, of means for effecting a reduction in brake pipe pressure in two stages including two equalizing reservoirs, two reduction reservoirs, means for venting fluid from both equalizing reservoirs to one of the reduction reservoirs to effect the first stage of reduction in brake pipe pressure and for venting fluid from only one of said equalizing reservoirs to both reduction reservoirs to effect the second

stage of reduction in brake pipe pressure, a timing reservoir, and a valve device having a position for establishing communication from one equalizing reservoir to the other and movable upon a predetermined reduction in pressure in the timing reservoir to another position in which said communica-

tion is cut off and communication is established between the two reduction reservoirs.

In testimony whereof we have hereunto set our hands this 21st day of October, 1927.
